(57) **CLAIM**

The ornamental design for a tongue anteriorizor, as shown and described.

DESCRIPTION

FIG. 1 is a perspective view showing my new design for a tongue anteriorizor;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a rear perspective view thereof; and,

FIG. 9 is a rear elevation view thereof shown in an environment of use.

The broken lines shown in FIG. 9 depict environmental subject matter only and form no parts of the claimed design.
